Application December 8, 1947, Serial No. 790,382

19 Claims. (Cl. 140—6)

1

My invention relates to machines suitable for use in the manufacture of wire fabric, such as that commonly known as poultry netting. Most machines in commercial use for this purpose embody an endless series of rows of twister gears supported from a suitable carrier in a pattern corresponding to that of the locks in the fabric which is to be made. The twister gears are provided with radial wire-receiving slots, and the gears of each row mesh with a common rack which, when moved longitudinally of itself, rotates each twister gear of the row and causes it to twist together the wires which have been previously deposited in its slot.

Practically all fabrics of the kind adapted to be made on a machine of the type to which this invention relates embody both line wires and mesh wires, the former extending longitudinally of the fabric and each of the latter following a zig-zag pattern into alternate association with adjacent line wires or with other mesh wires. Various mechanisms have been proposed for forming the mesh wires into the necessary zig-zag pattern. In one type of wire-forming mechanism, shown in my prior Patent No. 2,053,221, for example, the mesh wires are bent by abutments projecting outwardly of the gear-carrier from slidable bars which are mounted between the adjacent rows of twister gears. In another arrangement, the mesh wires are deflected alternately in opposite directions as they enter into association with the twister-gear carrier and attain their final form as they become seated in the twister-gear slots. In one such prior machine, the wires are deflected by abutments mounted on sliding rods associated with an auxiliary drum which meshes with the twister-gear carrier; and the wires thus deflected are deposited directly into the slots of the twister gears.

Each of the above noted old wire-deflecting mechanisms possesses one or more disadvantages. In mechanisms such as those shown in my prior patent above referred to, the available space between adjacent rows of twister gears limits the dimensions of the gears, of the gear supports, and of the sliding, wire-deflecting bars located between adjacent rows of twister gears; and as a result, it is frequently difficult to provide adequate strength and rigidity in such parts. In those machines in which the wire is deflected on an auxiliary drum and transferred directly therefrom to the twister gears, it is necessary to maintain rather accurate synchronization between movement of the auxiliary drum and movement of the twister-gear carrier, and it is moreover difficult to prevent interference between the wire-

2

supporting elements of the auxiliary member and the twister-gear supports of the gear carrier. In those constructions in which the wire is merely deflected laterally in opposite directions as it enters into association with the twister-gear carrier, it is difficult to provide in the deflected wires the slack necessary to permit them to be twisted together or about line wires without introducing excessive stresses. In order to provide slack, and/or in order to prevent interference between twister-gear support and wire-deflecting or depositing mechanism, machines of the two latter types frequently embody a twister-gear carrier so constructed that the distance between adjacent rows of twister gears varies in the operation of the machine.

It is the object of my invention to produce an improved poultry-netting machine which will possess advantages over other machines of which I am aware. More specifically, it is my object to provide a machine in which the mechanism employed to deflect the mesh wires of the netting into the necessary zig-zag pattern will be separate from the mechanism employed to form the locks in the fabric, thus making it possible for the design and construction of each mechanism to be independent of the other and for all parts to possess adequate rigidity, strength, and durability. Another object of my invention is to produce a wire deflecting mechanism which will provide the proper amount of slack in mesh wires to permit them to be twisted together or about line wires without introducing undue stresses. A further object of my invention is to produce an improved construction of the twister-gear support providing greater simplicity, strength, and rigidity and facilitating the removal and replacement of twister gears.

In carrying out my invention, I preform the mesh wires into the pattern which they are to occupy in the finished netting, and feed such preformed mesh wires to the lock-forming mechanism together with any marginal or other line wires which are to be embodied in the fabric. With all mesh wires and line wires properly positioned the lock-forming mechanism is operated to secure the mesh wires to each other or to line wires, and the finish fabric is then stripped from the lock-forming mechanism by an appropriate stripper roll. The preforming mechanism and the lock-forming mechanism are conveniently in the form of drums mounted for rotation in timed relationship on spaced, parallel axes. Each preforming drum may embody a series of abutments which, in the rotation of the drum, are moved relatively to each other to deflect each mesh

wire into the desired zig-zag pattern. In the specific embodiment of the invention illustrated and described in this application, the locks in the fabric are formed by twisting the wires thereof together, each set of wires to be so twisted together being seated in the radial slot of a twister gear which is subsequently rotated to form the lock. The twister gears are arranged on the twister drum in rows corresponding to the pattern of the locks in the finished fabric, and the twister drum is provided with an annular series of axially extending bars, one for each row of gears. Plates disposed on opposite sides of each bar project radially outwardly therebeyond and are provided in their opposed faces with recesses for rotatably receiving the hubs of the associated twister gears. Wedges disposed between adjacent bars of the twister drum are so formed that upon movement radially inwardly of the drum they will engage the plates on opposite sides of them and force such plates into firm engagement with their respectively associated bars. Disposed between each row of twister gears and its associated bar is an axially movable rack which meshes with the twister gears to rotate them jointly when the rack is moved axially of the drum. Because the mesh wires are fed to the drum in deflected condition, tension in the wires cannot be availed of to seat the wires in the slots of the twister gears; and for each set of mesh wires fed to the twister drum, I therefore provide a wire-seating roll provided with bars which mesh with the twister drum and engage the wires to force them positively to the bottoms of the slots in the twister gears. To facilitate meshing of the wire-seating rolls and the twister drum, the side surfaces of the plates which support the twister gears and the side surfaces of the bars on the wire-seating rolls are given a general involute shape. The general involute shape on the gear-supporting plates facilitates stripping of the finished fabric from the twister drum.

The accompanying drawings illustrate my invention:

Fig. 1 is a diagrammatic vertical section through a preferred form of machine; Fig. 2 is a somewhat diagrammatic elevation illustrating the discharge side of the machine; Fig. 3 is an elevation of the opposite side of the machine; Fig. 4 is an axial section through one of the forming drums on the line 4-4 of Fig. 6; Fig. 5 is a plan view of the forming drum; Fig. 6 is a transverse section through the forming drum on line 6-6 of Fig. 4; Fig. 7 is a side elevation of one of the forming-drum bars; Fig. 8 is a section on the line 8-8 of Fig. 7; Fig. 9 is a diagrammatic development of a forming drum and its related cam; Fig. 10 is a fragmental axial section through the twister drum; Fig. 11 is a section on the line 11-11 of Fig. 10; Fig. 12 is a fragmental end elevation in partial section of the twister drum; Fig. 13 is a fragmental section on the line 13-13 of Fig. 12; Fig. 14 is a fragmental isometric view of a guide tube used to guide preformed mesh wires to the twister drum; Fig. 15 is a timing diagram; Fig. 16 is a fragmental transverse section illustrating the meshing engagement of the twister drum and one of the rolls employed to seat the fabric-wires in the slots of the twister gears; Fig. 17 is an axial section through a wire-seating roll; Fig. 18 is an axial section and Fig. 19 a transverse section through the stripper roll; Fig. 20 is a fragmental transverse section on the line 20-20 of Fig. 10, with parts broken away; Figs. 21 and 22 are ele-

vations of opposite ends of the machine; Fig. 23 is a development of one of the cams employed to rotate the twister gears; Fig. 24 is a fragmental isometric development showing successive stages in the formation of the netting; Fig. 25 is a development of a portion of the twister drum in the plane of the netting; Fig. 26 is a view similar to Fig. 1 illustrating a modified form of machine embodying but a single forming drum; and Figs. 27 and 28 are fragmental developments showing the manner in which the netting is formed by the machine of Fig. 26.

General arrangement

As will be evident from the semi-diagrammatic illustrations constituting Figs. 1 and 2, my preferred machine embodies a base 23 and two spaced housings 24 and 25 extending between which there are a twister drum 26 and lower and upper forming drums 27 and 28, all arranged for rotation in the same direction about parallel, horizontal axes. One set of mesh wires, designated in Figs. 1 and 2 by the reference letter A, is fed into the machine near the bottom thereof, passing over guide rolls 29 and 30, around the forming drum 27, and through a guide tube 31 to the twister drum 26. The second set of mesh wires, designated by the reference letter B, enters the machine near the top, passing over guide rolls 33 and 34, around the forming drum 28, and through a guide tube 35 to the twister drum 26. Marginal or other line wires to be embodied in the fabric are conveniently fed to the machine with the mesh wires, but such line wires are bypassed around the forming drums and guide tubes, and are fed to the twister drum from auxiliary guide rolls 36. Two sets of line wires, designated C and D, are shown in Fig. 1, the set C entering the twister drum approximately with the mesh wires A, and the set D entering the drum approximately with the mesh wires B. The guide tubes 31 and 35 and the auxiliary rolls 36 are so arranged that the first set of mesh wires A, together with the line wires C, are deposited on the twister drum in advance of the point at which the second set of mesh wires B and line wires D are deposited.

The forming drums 27 and 28 operate in a manner, which will be described more fully hereinafter, to deflect the respective sets of mesh wires A and B in alternate directions into the form illustrated at A' and B' in Fig. 2. To seat both the deflected mesh wires A' and B' in the slots of the twister gears carried by the twister drum 26, I employ a pair of wire-seating rolls 40 and 41 which engage the deflected mesh wires A' and B' respectively as they enter into association with the twister drum 26 and force them radially inwardly thereof. The wire-seating roll 40, in addition to seating the first set of mesh wires A' in the twister gears may also be employed to seat the line wires C; and the roll 41 may be employed in similar manner to seat the line wires D. It will be understood that after the line wires and both sets of mesh wires are deposited in the slots of the twister gears, the twister gears will be caused to rotate in the continued rotation of the twister drum 26 to form the locks of the fabric. After such locks have been formed, the finished fabric, designated by the reference letter E, is stripped from the twister drum 26 by a stripper roll 43 and passes thence over guide rollers 44 and 45 to any convenient form of take-up mechanism (not shown).

Preforming mechanism

The two forming drums 27 and 28 are substantially identical, and it therefore will be necessary to describe but one of them in detail. To that end, details of construction of the drum 28 are shown in Figs. 4 to 8. As will be evident from those figures, the drum embodies a central supporting shaft 50 which is rotatably supported in any convenient manner from the housings 24 and 25. Mounted at spaced intervals along the shaft 50 are a plurality of spiders 51 each of which is provided at its periphery with an annular series of slots for the reception of two sets of alternating, longitudinally extending bars 52 and 53 which are arranged for axial movement relative to each other. In the machine shown, only one set of bars (the bars 53) move axially in operation of the machine, while the other bars remain in axially fixed positions; but this arrangement is not essential. To the outer face of each of the bars 52 and 53 there is secured an axially extending plate 54 carrying a series of axially spaced forming elements 55, conveniently in the form of U-shaped staples having ends which are received with a press fit in holes in the plate. The end spiders 51 are located outwardly beyond the ends of the plates 54 and are provided with keepers 56 which overlie the bars 52 and 53 to prevent their radial outward movement.

At one side of the machine, the shaft 50 carries a pair of shift-rod supporting spiders 60 and 61. Each of such spiders is keyed to the shaft 50, and the outer spider 60 is axially fixed on the shaft as by means of a set screw 62, while the inner spider 61 is axially slidable on the shaft. The adjacent end portions of the spider-hubs are provided exteriorly with screw-threads of opposite hand which are received within an internally threaded sleeve 63. By rotation of the sleeve 63 relative to the shaft 50, the spider 61 can be adjusted axially toward or away from the spider 60 for a purpose which will later become apparent.

The two spiders 60 and 61 are provided in their peripheries with annular series of aligned slots for the reception of axially movable shift-rods 65, one of such shift-rods 65 being provided for each of the axially movable bars 53 of the forming drum. Segmental keepers 66' overlying the rods 65 are secured to the spiders to hold the rods in place. Each shift-rod 65 projects inwardly beyond the inner spider 61 and is there connected to the adjacent end of one of the movable bars 53, conveniently through the medium of screws 53' and a thrust-transmitting key 65'. The opposite end of each shift-rod 65 projects outwardly beyond the outer spider 60 and is there provided with a cam-following roller 66 which is received between two cams 67 and 68 secured in any convenient manner upon the outer surface of a cam cylinder 64.

The two cams 67 and 68, between which cam-following rollers 66 on the shift-rods 65 are received, are complementarily shaped, as indicated in development in Fig. 9. In conformity with Fig. 4, it is assumed in Fig. 9, that the rods 65 and the rollers 66 they carry progress upwardly along the cam in the operation of the machine. As will be clear from Fig. 9, the cams are shaped to provide a roller-receiving race including a dwell 69, an inclined portion 70 in which the shift-rods 65 are moved outwardly of the drum, a second dwell 71, and a second inclined portion 72 in

which the shift rods are moved inwardly of the drum to return the rollers 66 to the dwell 69.

For convenience in describing the wire-forming operation which occurs as the rollers 66 traverse the cam-slot 69-70-71-72, I have in Fig. 9 designated as 54a those plates 54 which are secured to the stationary rods 52 and as 54b those plates which are secured to the shiftable rods 53. As each roller 66 traverses the dwell 69, each stable 55 on the associated movable plate 54b will be located a short distance inwardly beyond its corresponding staple 55 on the adjacent axially fixed plates 54a. As the drum rotates, the rollers 66 successively traverse the race-portion 70 to cause outward movement of the respectively associated shift-rods 65, bars 53, and plates 54b. In the outward movement of each plate 54b, the staples 55 thereon pass the corresponding staples on the axially fixed plates 54a. The plates 54b remain in their outer positions while their associated rollers traverse the dwell 71; and as the rollers pass through the inclined race-portion 72, the plates 54b are restored to their inner position. The cams 67 and 68 are so oriented about the axis of the drum that the mesh wires B enter into association with the drum near the end of the dwell 69, or at about the point indicated by the reference letter P in Fig. 9. Each wire B reaches the face of the drum between corresponding staples 55 on adjacent fixed and movable plates 54a and 54b, so that in the immediately ensuing outward movement of the plates 54b the wires will be deflected into the form indicated at B'. The deflected wires remain on the surface of the drum to a point, indicated at Q in Fig. 9, beyond the end of the dwell 71.

The relation between the angular extent of the race-portion 70, which produces outward movement of the movable plates 54b, and the angular interval between adjacent ones of such plates is of considerable importance. For any given throw of the plates 54b against a fixed force, an increase in the angular extent of the race-portion 70 would reduce the thrust transmitted from the cam 68 to the roller 66. However, the movement of each outwardly moving plate causes each wire to be drawn over the staples on all the following outwardly moving plates, the friction between such staples and the wire will create tension in the latter, and such tension will oppose the outward plate-movement. The longer the race-portion 70, the greater will be the number of plates 54b which are simultaneously engaged in outward, wire-deflecting movement, the greater will be the number of partially formed offsets in each wire, and the greater will be both the tension in the wires and the cam-reaction necessary to move the plates outwardly. If too many of the plates 54b are simultaneously engaged in outward movement, the tension created in the wires may be great enough to cause their breakage. In the particular arrangement shown in the drawing, the angular extent of the race-portion 70 is only about twenty percent greater than the angular interval between adjacent plates 54b with the result that no more than two of such plates are moving outwardly at the same time and during the greater portion of the outward movement of each plate no other plate is so moving.

The tension induced in the wires by the staples 55 on outwardly moving plates 54b tends to draw the fully deflected wires rearwardly over the staples on those plates 54b whose associated rollers 66 are traversing the dwell 71 in the cam-

race. It is consequently essential that enough of the plates 54b be retained at the outer limit of their movement to anchor the fully deflected wires effectively and prevent them from being drawn rearwardly. In the cam shown, the angular extent of the dwell 71 is four times the angular interval between adjacent plates 54b, and there consequently will always be at least four of such plates at the outer limit of plate-movement. With four plates so located, the deflected mesh wires are effectively anchored against rearward movement.

As previously indicated, the point Q at which the deflected mesh wires leave the drum is located beyond the point at which the dwell 71 terminates. In consequence, the movable plates 54b have begun their inward movement, to free the staples from any binding engagement with the wires, before the wires leave the drum; and the deflected wires thus leave the drum without opposition.

The forming drum 27 may be identical with the drum 28 and the movable plates it carries may be reciprocated by a cam 67'-68' (Fig. 3) identical with the cam 67-68 above described. It will of course be understood that the orientation of the cam 67'-68' about the axes of the drum 27 with respect to the tangential stretches of undeflected and deflected mesh wires A and A' will be the same as the orientation of the cam 67-68 with respect to the tangential stretches of the mesh wires B and B'. See the timing diagram, Fig. 15.

The extent to which the mesh wires are offset by the associated forming roll will depend upon the axial positions of the stationary plates 54a relative to that of the cam 67-68. Opposite ends of the bars 52, which bear such stationary plates, abut respectively (see Fig. 4) against the inner end of the inner spider 61 and the inner face of a collar 73 which is axially adjustable along the shaft 50 and adapted to be held in any desired position by a set-screw 73. By rotating the sleeve 63 which interconnects the two spiders 60 and 61, the axial position of the inner spider can be varied to vary the axial position of the bars 52 and plates 54a. When the inner spider has been adjusted to position the plates 54a properly, the collar 73 is forced against the ends of the bars 52 and the set-screw 73 is tightened.

Lock-forming mechanism

The twister drum comprises a shaft 75 (see Fig. 2) rotatably supported from and extending between the housings 24 and 25. Between the housings, such shaft has rigidly mounted upon it a plurality of spiders 76 (Fig. 10) provided in their respective peripheries with series of aligned slots in which axially extending bars 77 are mounted. The bars 77 have a width greater than the depth of the bar-receiving slots in the spiders 76, and hence project radially outward beyond the peripheries of such spiders. To hold the bars in position, they are notched at their outer corners, and keepers 78 (Figs. 10 and 12) received in the notches of adjacent bars are secured to end spiders 76 by screws 79.

Each of the bars 77 has associated with it two series of gear-supporting plates 79 which are located on opposite sides of the bar, which extend longitudinally of the drum, and which project radially outward beyond the outer edge of the bar. In each space between plates 79 respectively associated with adjacent bars 77 there is disposed a wedge 80. The wedges 80 extend lon-

5 gitudinally of the drum and are provided in the planes of the spiders 76 with radial openings for the reception of screws 81 extending into screw-threaded holes in the spiders. It will be apparent that by tightening the screws 81, the two series of gear-supporting plates 79 on the opposite sides of each wedge will be forced tightly against the bars 77 respectively associated with them.

At intervals along its length, each of the bars 77 is provided with openings for the reception of dowel pins 85 (Figs. 10 and 12) which, in the construction shown, project from both faces of the bar to be received in openings 85' in the associated plates 79, whereby the plates are located in definite position both radially and longitudinally of the drum. The distance between the ends of the dowels in adjacent bars 77 is made greater than the thickness of plates 79 which receive such dowels, so that upon removal of the wedge 80 any adjacent plate may be slipped off the dowels which it receives, as indicated in Fig. 12, and removed from the drum.

Near their outer edges and in their opposed faces, the plates 79 associated with each bar 77 are provided with aligned recesses 87 which rotatably receive the hubs 88 of twister gears 89. Each of the twister gears 89 is provided between two adjacent teeth with a radial slot 90 extending inwardly beyond the gear-axis; and at each twister gear the plates 79 are slotted, as shown at 79', to permit the fabric wires to enter the twister-gear slot.

The twister gears of adjacent rows on the drum are disposed in staggered relationship corresponding to the pattern of locks in hexagonal-mesh wire fabric. Between adjacent gears the plates 79 are slotted, as indicated at 91, to receive marginal or other line wires. Beneath each row of gears there is disposed a toothed rack 92 which meshes with the gears and which is slidably supported by the associated bar 77 and plates 79. As will be obvious, the gears of each row can be rotated in unison by axial movement of their associated rack 92.

Adjacent racks 92 project outwardly beyond opposite ends of the drum for connection to rack-moving mechanisms located respectively in the housings 24 and 25 and capable of moving the racks axially of the drum as the latter rotates. The rack-moving mechanisms at opposite ends of the drum are substantially identical, and it therefore will be necessary to describe but one of them, that within the housing 25 being selected for the purpose.

Such rack-moving mechanism (see Figs. 10 and 11) comprises a hollow cam-cylinder 95 which is disposed concentric with the shaft 75 and non-rotatably connected to the outer wall of the housing 25, such cylinder being provided with bearing sleeves 96 rotatably supporting the shaft 75. At the inner end of the cam cylinder 95 a gear 97 is secured to the shaft 75, and between such gear and the adjacent end of the cam cylinder I provide a thrust bearing 98. A second gear 99 corresponding in size to the gear 97 is rotatably supported from the cam cylinder 95 adjacent the outer end thereof.

For each of the racks 92 which projects toward it from the adjacent end of the drum, the gear 97 is provided with an opening slidably receiving a rod 101 operatively connected to the associated rack 92. Conveniently, each rack 92 is provided at its end with an outwardly projecting bracket 102 which is received between nuts 103 mounted on the screw-threaded end of the rod 101. The

opposite end of each rod 101 is secured to a slide 105 mounted for axial sliding movement upon adjacent guides 106 which extend between the gears 97 and 99 and which are conveniently secured in aligned openings in such gears, as by screws 107 mounted in the gears. Each slide 105 carries a roller 108 which co-operates with inner and outer cam segments 109 and 110 secured to the cylinder 95.

A development of the cam 109-110 is illustrated in Fig. 23. In agreement with Figs. 10 and 11, it is assumed in Fig. 23 that the cam-following rollers 108 progress upwardly along the cam in the rotation of the twister drum. The inner cam segment 109 has a flat portion 109a providing a dwell during which the rollers 108, rods 101, and racks 92 are at the inner limit of their movement, an outwardly inclined portion 109b which forces the rollers, bars, and racks outwardly, and an inwardly inclined portion 109c permitting a slight inward movement of the rollers, bars, and racks. The outer cam segment 110 has an inwardly inclined portion 110a complementary to the inwardly inclined portion 109c of the inner cam segment, a flat portion 110b providing a dwell during which the finished fabric is stripped from the twister drum, and an inwardly inclined portion 110c which acts on the rollers 108 to force them inwardly and restore the bars 101 and racks 92 to their inner position.

The machine is so arranged that both sets of deflected mesh wires, together with the line wires, will be deposited in the slots 90 of twister gears meshing with racks 92 whose associated rollers 108 are traversing the dwell 109a. As the rollers 108 successively come into engagement with the inclined cam-portion 109b, they are moved outwardly to cause outward movement of the racks and rotation of the twister gears to form the locks in the fabric. The axial extent of the inclined cam portion 109b is somewhat greater than that necessary to rotate the twister gears through an integral number of complete revolutions, and at the conclusion of the lock-forming rotation of the twister gears the slots 90 therein will have been carried through a small angle beyond a position of alignment with the slots 79' in the plates 79. However, the axial extent of the inwardly inclined portions 109c and 110a is such that at their termination the twister gears will have been rotated rearwardly to bring their slots into coincidence with the slots 79'. If the twister gears terminated their lock-forming rotation with the gear slots 90 in alignment with the slots 79', the elasticity of the wires would cause them to bear with considerable force against the sides of the gear-slots, thus creating a frictional drag which would seriously impede the operation of stripping the locks of the finished fabric from the gear slots. By continuing lock-forming rotation of the twister gears until the slots 90 therein have moved beyond the slots 79', and by subsequently rotating the twister gears in the reverse direction until their slots come into alignment with the slots 79', the torsional stress in the wires is relieved and the locks may readily be removed from the gear slots.

The rack-operating mechanism located within the housing 24 is identical with that above described except that the cam 109-110 is of opposite hand.

To facilitate removal of any of the guides 106 for the purposes of inspection or replacement, the outer end wall of each of the housings may be provided with an arcuate slot 112 (Figs. 10

and 21) opposite the ends of such guides and having a width greater than the guide-diameter. By operating the machine to bring opposite the slot 112 any guide which it is desired to remove, 5 and by removing the screws 107 which hold such guide in place in the gears 97 and 99, the guide can be withdrawn through the slot.

The effort required to produce lock-forming rotation of the twister gears involves axially directed forces of substantial magnitude. I have found it desirable to confine such axially directed forces as far as possible to the twister drum and rack-operating mechanisms and to isolate them from the housings 24 and 25. To aid in obtaining that result, I employ (Fig. 10) an adjustable spacer at each end of the twister drum between the inner gear 97 and the adjacent end spider 76. Such a spacer conveniently comprises inner and outer screw-threadedly interconnected sleeves 115 and 116, as shown in Fig. 10. The inner sleeve, as there shown, has a loose fit on the shaft 75 and is provided at its outer end with an annular flange carrying set screws 117 which bear against the adjacent end of the gear 97 to oppose rotation 15 of the sleeve 115 relative to the shaft and gear. The outer sleeve 116 bears against the outer face of the adjacent end spider 76. When properly adjusted, the adjustable spacer 115-116 takes up all axial lost motion between the gear 97 and 20 the twister drum. A lock nut 118 operates when tightened to hold the sleeves 115 and 116 in the proper position of relative adjustment. With such an arrangement, the inwardly directed axial thrusts exerted by the rollers 108 on the inner 25 cam 109 are transmitted to the cam cylinder 95 and through the thrust bearings 98, gears 97, and adjustable spacers 115-116 to opposite ends of the twister drum. If desired, a portion of the 30 thrust imposed on each of the inner gears 97 may be transmitted directly to the shaft 75 through the use of a set screw 119 in each of such 35 gears.

To prevent the transmission to the housings 24 and 25 of any of the axial faces incident to the lock-forming operation, cylindrical pins 120 extending through the outer housing wall and into the adjacent cam cylinder are employed to hold the cam cylinder against rotation.

A preferred form of guide tube for guiding each 50 of the preformed mesh wires into association with the twister drum is shown in Fig. 14, which illustrates the tube 31. As there shown, the tube comprises a pair of parallel plates 31a and 31b one of which is provided with spaced, parallel 55 ribs 31c having a height somewhat greater than the diameter of the mesh wires. The plates, with the ribs 31c, define a plurality of parallel slots each of which freely receives and guides one of the preformed mesh wires A'.

Wire-seating and stripper rolls

The construction of the wire-seating rolls 40 and 41 which operate to seat the wires of the fabric in the bottoms of the twister gear slots is 60 illustrated in Figs. 16 and 17. Each wire-seating roll comprises a shaft 121 supported in suitable bearings 121' from the inner walls of the housings 24 and 25. Rigidly mounted on the shaft 121 are a plurality of axially spaced spiders 122 provided in their peripheries with annular 65 series of slots for the reception of axially extending bars 123. Within the radial limits of the bar-receiving slots, each of the spiders 122 is provided in its opposite faces with annular grooves 124 adapted to receive pins 125 mounted in and 70

projecting from the bars 123. The spacing of the pins 125 corresponds to the spacing of the spiders 122, so that each bar can be brought into association with the spiders by moving it first radially into the spider-slots and then axially until the pins 125 become seated in grooves 124 in the several spiders. Adjacent bars 123 are oppositely arranged in the drum so that the pins 125 they respectively carry will be seated in the grooves 124 in opposite faces of the spiders 112. In such an arrangement, alternate bars at each end of the drum will project axially outward beyond the remaining bars. (Compare the two bars 123 illustrated in Fig. 17.) At each end of the roll a collar 126 is slidably mounted on the shaft 121 and is adapted to be held in fixed axial position on the shaft as by a set screw 127. The diameter of the collars 126 is great enough to permit them to overlap radially the ends of the bars 123, and each collar is provided with openings for the reception of screws 128 which enter screw-threaded holes in the adjacent end spider 122. Tightening of the screws 128 forces the collar inwardly of the roller and causes it to seat firmly in the grooves 124 of all the spiders the pins 125 on the bars which it engages. If it becomes necessary to remove one of the bars 123 for replacement or repair, it is necessary only to loosen the screws 127 and 128 associated with the collar 126 which engages the end of the bar to be replaced, thus permitting such collar and the bar to be moved axially outward of the roll until the pins 125 on the bar are free of the grooves 124, whereupon the bar can be removed radially.

From Fig. 16 it will be apparent that the bars 123 on each of the wire-seating rolls 40 and 41 are received in the twister drum in the spaces between adjacent pairs of plates 79. The distance between the axes of each roll and the twister drum is such that the outer edges of the plates 123 will force the wires of the fabric to the bottoms of the slots in the twister gears.

It is unnecessary to provide means for driving the wire-seating rolls 40 and 41, as the effort required to rotate them is so slight that they can be driven by engagement with the fabric wires and/or the plates 79 on the twister drum. To prevent interference between the plates 79 on the twister drum and the bars 123 of the wire-seating rolls, the outer portions of the faces of such plates and bars are desirably given the generally involute shape indicated at 130 in Fig. 16.

The stripper roll 43 is illustrated in Figs. 18 and 19. As there shown, the roll comprises a shaft 132 rotatably supported from the housings 24 and 25 through bearings 133. The shaft 132 carries a plurality of axially spaced spiders 134 provided in their periphery with slots for the reception of axially extending bars 135. To one side face of each of the bars 135 there are secured an axially extending series of plates 136 which project radially outward beyond the bars 135 and the outer edges of which are serrated to provide teeth 137 adapted to enter openings in the finished fabric.

Driving mechanism

For the purpose of driving the machine (see Fig. 3) I mount on one end of the frame 23, conveniently outwardly beyond the housing 24, an electric motor 140 or other source of power operatively connected to a speed reducer 141. The speed reducer is in turn connected, as through gearing 142, with a synchronizing shaft 143

which extends through the housing 24, parallel to the twister drum, and into the housing 25, being rotatably supported from the housing by bearings 143'. Within each housing, a pair of equal-diameter gears 144 are secured to the shaft 143 in position to mesh with the gears 97 and 99 of the rack-operating mechanism mounted in such housing. By such an arrangement, the two gears 97 and 99 are independently driven and it is possible to mount the gear 99 on the cam cylinder 95 rather than on the shaft 75 and, at the same time, to eliminate bending stresses in the guides 106 extending between the two gears 97 and 99. As each gear 97 is keyed to the twister-drum shaft 75, rotation of the synchronizing shaft 143 will result in rotation of the twister drum.

For the purpose of driving the two forming drums 27 and 28, the shafts 50 thereof project outwardly beyond the outer wall of the housing 25 where they carry sprockets 145. The shaft 75 likewise projects outwardly beyond the outer wall of the housing 25 and is there provided in the plane of the sprockets 145 with a drive sprocket 146. A driving chain 147, shown as of double width, is trained over the sprockets 145 and 146 and also over an idler 148 by means of which the chain may be tightened.

While the two forming drums 27 and 28 rotate in the same direction as does the twister drum, the stripper roll 43, which is also positively driven, rotates in the reverse direction. To provide the reverse rotation of the stripper roll 43, a pair of parallel countershafts 148 and 149 are mounted within the housing 25 and are operatively connected by gears 150. One of such countershafts, shown as the shaft 148, projects outwardly beyond the outer wall of the housing 25 where it is provided with a sprocket 151 meshing with a chain 152 which in turn meshes with a second sprocket 153 on the shaft 75. The other countershaft 149 projects inwardly through the inner side wall of the housing 25 and is operatively connected to the shaft 132 of the stripper roll 43 by a chain drive 153.

Operation

In setting up the machine for operation, the mesh wires A are led over the rollers 29 and 30 to the forming drum 27, being woven through the staples 55 approximately to that point at which the deflected wires will leave such drum. The mesh wires B are similarly trained over the rollers 33 and 34 and onto the forming drum 28. The machine is then started and run until the deflected wires A' and B' formed by the drums 27 and 28 are long enough to pass through the guide tube 31 and 35 and into the slots of the twister gears on the twister drum 26. The machine is then stopped, and the deflected mesh wires are passed through the respective guide tubes to the twister drum and engaged in the slots of the twister gears. The marginal wires C and D, or other line wires which by-pass the forming drums 27 and 28, are led over the guide rolls 36 and into the twister gear slots. As such line wires are not deflected out of their respective vertical planes, they can readily be drawn over the path they are to follow without the necessity of operating the machine.

After both sets of mesh wires and the line wires have been brought into the slots of the twister gears, the machine is again started until enough fabric has been formed to be engaged by the stripper roll 43. The end of the fabric is then

engaged with the teeth 137 of the stripper roll, and the machine is again started, the end of the fabric being led over the roller 44 and around the roller 45 to the take-up mechanism. The roller 44 is conveniently mounted upon the synchronizing shaft 143; but as it rotates in a direction opposite to that of the synchronizing shaft, it is desirably mounted thereon through the roller or other anti-friction bearings 155.

With the leading end of the fabric engaged with the take-up mechanism, the machine is ready for continuous operation, the various steps in which are indicated in the timing diagram constituting Fig. 15, and in the developments constituting Figs. 9 and 24. As will be evident from Figs. 9 and 15, the mesh wires A enter into association with the forming drum 27 at the point P where the plates 54b are at the inner limit of their movement. As the forming drum 27 rotates, the plates 54b are moved outwardly to form the offsets in the wires, such offsets being completed before the deflected mesh wires A' leave the forming drum at the point Q. The deflected mesh wires A' pass through the guide tube 31 into the slots of the twister gears, being forced to the bottom of such slots by the blades 123 of the wire-seating roll 40. The mesh wires B are similarly deflected by the forming drum 28; and the deflected wires B' pass through the guide tube 35 and into the slots of the twister gear. Referring to Figs. 15 and 24, the mesh wires A' together with the line or marginal wires C reach the bottoms of the slots in the twister gears at the point S, while the deflected mesh wires B' and the other line or marginal wires D are seated in the bottoms of the twister slots at the point T. Immediately beyond the point T, the rollers 108 at opposite ends of the machine engage the inclined portions 109b of the twister cams to draw the associated racks 92 outwardly and cause the twister gears to rotate to form the locks in the fabric. Such lock-forming rotation of the twister gears, including the overtravel thereof and the return to the position in which their slots are in alignment with the slots 79' of the plates 79, is completed before each row of twister gears reaches the point U, at which the finished fabric leaves the twister drum to pass around the stripper roll 43.

Beyond the point U, the rollers 108 engage the inwardly inclined portions 110c of the cams 110 and are moved inwardly to restore the racks 92 to their inner positions, thus positioning the twister gears again to receive the line and mesh wires

Machine of Fig. 26

The modified form of machine illustrated in Fig. 26 embodies a design which is especially suited for the manufacture of relatively coarse hexagonal netting, although it can if desired be embodied in a machine for the manufacture of netting of smaller mesh. The machine embodies a twister drum 26', a pair of angularly spaced wire-seating rolls 40' and 41', and a stripper roll 43' generally similar in construction and mode of operation to the corresponding elements of the machine above described. In contrast to the previously described machine, however, the machine of Fig. 26 embodies a single preforming drum 160. The drum 160, like the drums 27 and 28, embodies alternating axially fixed and axially movable plates 54a and 54b provided with wire-engaging abutments 55; but for netting of any given mesh-size, the spac-

ing between adjacent staples 55 on each plate 54 of the drum 160 will be only half as great as in the case of the staples on the drums 27 and 28.

5 In the machine of Fig. 26, all mesh wires are fed into the forming drum 160 together, passing over appropriate guide rolls including the rolls 30. In the operation of the forming drum the mesh wires are bent into zig-zag pattern as 10 shown in Fig. 27; and on leaving the drum 160, one set of alternate wires, designated as A', pass directly to the twister drum 26', while the other set, designated as B', pass over a guide 161 and enter into association with the forming drum 26' 15 at a later point in the rotation of the latter. As in the previously described machine, the wire-seating roll 40' operates to seat the mesh wires A' in the slots of the twister gears, while the wire-seating roll 41' performs the same 20 operation on the second set of mesh wires B'.

The lengths of the respective paths followed by the wires A' and B' differ by an amount equal to an odd multiple of the linear distance between the center-lines of adjacent fixed and 25 movable plates 54 on the drum 160. As a result, when the second set of mesh wires B' is deposited in the drum 26' the hexagon-mesh pattern is completed, as shown in Fig. 28. Thereafter, the twister gears are rotated as in the 30 machine of Figs. 1 to 23 to form the locks in the netting, and the netting is stripped from the twister drum by the stripper roll 43'.

In the drawings, I have contemplated a netting in which the only line wires are those at 35 the margins. It will be obvious, however, that additional line wires can be distributed throughout the width of the netting, if desired. It will likewise be obvious that my invention is not limited to the manufacture of hexagonal netting 40 but may also be employed to produce the so-called "straight-line" netting, which embodies a series of laterally spaced, parallel line wires and a single set of mesh wires, with each of the 45 mesh wires intertwined alternately with two adjacent line wires. Since straight-line netting embodies only a single set of mesh wires, a machine for making it need embody but one pre-forming drum.

I find it desirable to make the effective length 50 of each of the staples 55 of the preforming drum somewhat greater than the over-all thickness of each assembly embodying one of the twister-drum bars and its two associated plates, with the result that the longitudinally extending stretches 55 in the preformed wires will be longer than the locks in the finished fabric. This is indicated in Fig. 25, where a dotted-line showing of the preformed wires and the staples is superposed on a representation of the finished netting in place 60 in twister gears. The extra length of the longitudinal stretches of the preformed wires provides slack which prevents the twisting operation from creating undue tension in the wires. Variations in the exact amount of slack so provided can be effected by varying the axial position of the fixed bars 53 of the forming drum in the manner previously described. Such adjustment of the bars 52, which is employed to increase the amount of off-setting of the mesh wires when more slack 65 is desired and to decrease the amount of off-setting when less slack is desired, may result in so forming the mesh wires that the lateral distance between adjacent longitudinal wire-stretches will differ from the distance, measured 70 axially of the twister drum, between the twister 75

gears of adjacent rows. This is immaterial, however, because the slots 79 in the gear-supporting plates are provided with widened mouths, as shown in Fig. 13, and hence will receive the mesh wires and permit them to be seated in the twister-gear slots by the seating rolls 40 and 41 even if the wires, as preformed, are not in precise registry with the lower portions of the slots. The precise control of slack which may be effected by adjustment of the bars 52 is very advantageous, as it provides for the correction of manufacturing inaccuracies and permits accommodation to be made for wires of different diameter.

Another advantage of my invention arises from the fact that the mechanism which deflects the mesh wires into the desired pattern is entirely separate from the twister drum. This permits relatively great freedom of design, in that the twister-gear support need not be arranged to accommodate wire-shifting elements between adjacent rows of twister gears nor the axially shiftable wire-preforming bars arranged to provide space between them for rows of twister gears. The diameter of each preforming drum and the number of axially shiftable bars embodied in it may be independent of the diameter of the twister drum and the number of rows of twister gears. The diameter of the twister drum may be made smaller, and the number of rows of twister gears correspondingly reduced, because it is unnecessary to devote portions of each revolution of the twister drum to wire-deflecting operations.

Still another advantage of my invention arises from the fact that the amount of intertwisting of the wires forming each lock depends upon the initial arrangement of the wires with respect to the direction of rotation of the twister gear forming the lock. For example, with the mesh wires A' and B' arranged tangentially and axially of the twister drum as indicated in Fig. 24, if the twister gears which receive the pairs of superposed wires on the line T-T are assumed to rotate in a counterclockwise direction during the lock-forming operation, each end of each lock will possess one full turn of twist for each rotation of the twister gears. However, if the respective positions of the two sets of wires A' and B' axially and circumferentially of the drum were reversed, the first half-turn of rotation of each twister gear on the line T-T would merely invert the wires associated with it, only thereafter would intertwisting begin, and each end of each lock would possess one-half turn less than in the previous instance. By my invention it is possible to control, and to vary if desired, the initial arrangement of the wires with respect to the direction of lock-forming rotation of each row of twister gears. In the machines illustrated and above described, the axial disposition of each set of mesh wires is determined by the position of the associated guide-tube 31, and can be varied by moving such guide tube parallel to the twister-drum axis. The presence of the free stretch of each preformed mesh wire between its forming drum and the associated guide tube makes it unnecessary to change the axial position of the forming drum if the position of the guide tube is changed. The circumferential disposition of each set of mesh wires in the forming drum might be varied by providing slack in the free stretches of the preformed mesh wires; but I prefer to vary it, and to avoid such slack, by changing the relative timing of the twister drum and each preforming drum. Such change in timing can be provided for in any convenient

manner, as by mounting the sprockets 145 (Fig. 21) for angular adjustment relative to the respective forming-drum shafts 50.

It will be understood, of course, that without changing the amount of lock-forming rotation of the twister gears the variation in the amount of intertwisting at each lock can be varied by only one-half turn and that to effect such variation both the axial and circumferential disposition of each set of mesh wires on the twister drum will be varied by definite amounts. Specifically, axial variations will be by an amount equal to one-half the distance between adjacent twister gears in any row and circumferential shifting will be by an amount equal to the distance between adjacent rows of twister gears. In ordinary mesh patterns, axial shifting of mesh wires must always be accompanied by circumferential shifting in order to prevent the longitudinally extending portions of the mesh wires from entering the slots 91 instead of the twister-gear slots.

In the case of twister gears which receive a marginal or other line wire, the amount of intertwisting of such line wire with the adjacent mesh wire can be varied by a half-turn by varying the order in which those wires are deposited in the twister-gear slots. With the line-wire guide rolls 38 arranged as indicated in full lines in Fig. 1, the mesh wires A' will be deposited on the twister drum before the margin wires C are deposited; but with the guide rolls 38 shown as indicated in dotted lines in Fig. 1, deposit of the margin wires will precede deposit of the mesh wires. Fig. 24 illustrates the condition resulting from use of the dotted-line arrangement shown in Fig. 1.

While I have shown and described my invention as embodied in machines for producing fabric of uniform mesh-width, it will be obvious that by utilizing the principles of my prior United States Letters Patent No. 2,204,602, granted June 18, 1940, the present invention can be utilized in the production of fabric in which the mesh-width is graduated.

45 I claim as my invention:

1. In a machine for making wire netting, an endless series of spaced, parallel rows of slotted twister gears, a movable support therefor, means for feeding two sets of mesh wires, a wire-forming mechanism associated with each set of mesh wires and operating in timed relation with said twister-gear support, each said mechanism operating to form in each of its associated wires a series of lateral off-sets, guides for guiding both sets of formed mesh wires into association with said support at spaced points thereon, means at each of such points for forcing formed mesh wires into the slots of the twister gears, and mechanism operable in the movement of said support for rotating the gears of each row after the preformed mesh wires have been deposited in the slots thereof.

2. The invention set forth in claim 1 with the addition that said twister-gear support is of cylindrical form and rotatable about its axis, each of said wire-forcing means comprising a drum rotatably mounted at one side of said carrier for rotation about an axis parallel to the carrier axis, said drum having an annular series of axially extending, wire-engaging bars successively receivable between adjacent rows of twister gears on said carrier.

3. In a machine for making wire netting, a rotatable drum, an annular series of pairs of opposed, axially extending plates carried by said

drum, a row of slotted twister gears located between and pivotally supported from the plates of each pair, means for depositing pairs of wires in the slots of the twister gears, means operable in the rotation of said drum following deposit of the wires in the gears of each row for rotating such gears to twist the wires of each pair together and form a netting, a stripper roll spaced from said drum and over which said netting passes, said stripper roll having wire-engaging elements which mesh with and drive the netting, and means for driving said drum and stripper roll in timed relation, the leading face of the leading plate of each pair of plates having a general involute form.

4. In a machine for making wire netting, a rotatable drum having an annular series of axially extending bars, a pair of plates disposed on opposite sides of each of said bars and projecting radially outward beyond the bar, twister gears disposed between and rotatably supported from each pair of plates outwardly beyond the associated bar, means for rotating said gears, said means including a rack disposed between the gears and the associated bar, axially extending wedges disposed between the bars in position to engage said plates, and means for moving said wedges radially of the drum to force the plates into contact with their respectively associated bars.

5. In a machine for making wire netting, a rotatable drum having an annular series of axially extending bars, a pair of plates disposed on opposite sides of each of said bars and projecting radially outward beyond the bar, twister gears disposed between and rotatably supported from each pair of plates outwardly beyond the associated bar, means for rotating said gears, axially extending wedges disposed between the bars in position to engage said plates, and means for moving said wedges radially of the drum to force the plates into contact with their respectively associated bars.

6. In a machine for making wire netting, a rotatable drum having an annular series of axially extending bars, a pair of plates disposed on opposite sides of each of said bars and projecting radially outward beyond the bar, twister gears disposed between and rotatably supported from each pair of plates outwardly beyond the associated bar, means for rotating said gears, each bar and its associated plates having cooperating elements rigid respectively with the bar and plates and having interengaging surfaces which extend tangentially of the drum for limited extents for locating the plates radially and axially of the drum, said elements being disengageable by tangential movement of the plates to permit their radial withdrawal, and means for forcing each plate against the side of its associated bar.

7. In a wire netting machine, means for feeding two sets of mesh wires successively to separated forming and joining stations, forming mechanism acting on each set of mesh wires at a forming station to provide in each wire a series of laterally offset, longitudinally extending portions interconnected by transversely extending portions, means guiding the two sets of formed mesh wires into association with each other with longitudinally extending portions of the wires of one set respectively juxtaposed with longitudinally extending portions of wires of the other set to form a mesh pattern, and means at the joining

station for securing such juxtaposed longitudinally extending portions together.

8. The invention set forth in claim 7 with the addition that said securing means comprises a plurality of rotatable twisters arranged in predetermined pattern, each of said twisters being provided with a radial slot adapted to receive juxtaposed longitudinally extending wire-portions.

9. In a machine for making wire netting of the type in which generally longitudinally extending wires include mesh wires each offset laterally into alternate association with wires on opposite sides of it, means for securing the wires together in pairs at their points of association, means for feeding the wires over predetermined paths to said securing means, and forming means located in advance of said securing means along the path traversed by each mesh wire for pre-forming it into the pattern it is to occupy in the finished fabric.

10. The invention set forth in claim 9 with the addition that said securing means comprise a plurality of rotatable twisters arranged in predetermined pattern, each of said twisters being provided with a radial slot adapted to receive juxtaposed longitudinally extending wire-portions.

11. In a machine for making wire netting of the type in which generally longitudinally extending wires include mesh wires each offset laterally into alternate association with wires on opposite sides of it, means for securing the wires together in pairs at their points of association, means for feeding the wires over predetermined paths to said securing means and mechanism located in advance of said securing means along the path traversed by each mesh wire for pre-forming each mesh wire into the pattern it occupies in the finished fabric, said preforming means comprising a rotatable drum, an annular series of axially extending bars carried by said drum, locating means for holding alternate ones of said bars in fixed axial position, means for successively reciprocating the remaining bars as the drum rotates, wire-engaging abutments carried by said bars in positions to engage and form the wires as the reciprocating bars are moved in one direction, said bar-locating means being adjustable to vary the axial positions of the bars it locates.

12. The invention set forth in claim 9 with the addition that said forming means is adjustable to vary the extent of offsetting of the mesh wires.

13. In a machine for making wire netting of hexagonal mesh, means for feeding mesh wires in parallel relationship, preforming mechanism acting on said wires as they are fed for producing in them similar semi-hexagonal offsets disposed in rows extending transversely of the wires, guiding means for separating the formed wires into two sets each composed of alternate wires and for guiding the two sets of wires respectively over different but eventually coinciding paths, said guiding means being so constructed and arranged that the paths respectively followed by the two sets of wires differ in length to an extent such that when the two sets of wires come into association at the point of coincidence of such paths they will complement each other to form a hexagonal mesh.

14. A method of producing hexagonal-mesh wire netting, comprising preforming two sets of mesh wires at a preforming station to produce in each wire of each set a series of semi-hexagonal offsets adjacent ones of which include longitudinally extending, laterally offset portions,

feeding the two sets of preformed wires to a joining station spaced from said preforming station, superposing the two sets of wires at said joining station in complementary relationship to produce a hexagonal mesh pattern with longitudinally extending portions of the wires of one set coinciding with longitudinal portions of the other set, and securing the coinciding wire-portions together.

15. A method of producing hexagonal-mesh wire netting, comprising preforming two sets of mesh wires at a preforming station to produce in each wire of each set a series of semi-hexagonal offsets adjacent ones of which include longitudinally extending, laterally offset portions, feeding the two sets of preformed wires to a joining station spaced from said preforming station, superposing the two sets of wires at said joining station in complementary relationship to produce a hexagonal mesh pattern with longitudinally extending portions of the wires of one set coinciding with longitudinal portions of the other set, and intertwisting the coinciding wire-portions.

16. The method set forth in claim 14 with the addition that the wires of both sets are preformed simultaneously while moving longitudinally of themselves in parallel relationship and while the wires of one set alternate with wires of the other set, the two sets of preformed wires being then separated and guided over paths of different length into said complementary relationship.

17. In a machine for making wire netting of the type in which generally longitudinally extending wires include mesh wires each offset laterally into alternate association with wires on opposite sides of it, means for securing the wires together in pairs at their points of association, and mechanism for preforming each mesh wire into the pattern it occupies in the finished fabric, said preforming means comprising a rotatable drum, an annular series of axially extending bars carried by said drum, means operable in the rotation of said drum for producing relative axial movement of adjacent ones of said bars, wire-engaging abutments carried by said bars in positions to engage and form the wires as the bars move relatively, and adjustable means for varying the relative movement of adjacent bars to vary the degree of offsetting in the preformed mesh wires.

18. The method of producing wire netting of the type in which each of a plurality of mesh

wires is offset alternately into association with and secured to adjacent wires on opposite sides of it, which method comprises the steps of feeding the mesh wires over predetermined paths successively to separated preforming and joining stations, preforming the mesh wires at the preforming station to produce in each a series of longitudinally extending, laterally offset portions interconnected by transversely connected portions, bringing the preformed mesh wires into association at the joining station with the wires to which they are to be secured with the laterally offset portions respectively coinciding with the wires to which they are to be secured, and securing each offset portion to the coinciding wire.

19. The method of producing wire netting of the type in which each of a plurality of mesh wires is offset alternately into association with and secured to adjacent wires on opposite sides of it, which method comprises the steps of feeding the mesh wires over predetermined paths successively to separated preforming and joining stations, preforming the mesh wires at the preforming station to produce in each a series of longitudinally extending, laterally offset portions interconnected by transversely connected portions, bringing the preformed mesh wires into association at the joining station with the wires to which they are to be secured with the laterally offset portions respectively coinciding with the wires to which they are to be secured, and intertwisting each offset portion and the coinciding wire.

HARRY L. KITSELMAN.
